UNITED STATES PATENT OFFICE.

GEORGE H. COLTON, OF HIRAM, OHIO.

SUPPORT FOR RADIATORS OR THE LIKE.

SPECIFICATION forming part of Letters Patent No. 755,111, dated March 22, 1904.

Application filed September 28, 1903. Serial No. 174,902. (No model.)

To all whom it may concern:

Be it known that I, GEORGE H. COLTON, a citizen of the United States, and a resident of Hiram, county of Portage, and State of Ohio, have invented a new and useful Improvement 5 in Supports for Radiators or the Like, of which the following is a specification, the principle of the invention being herein explained and the best mode in which I have contemplated applying that principle, so as to distinguish it from other inventions.

My invention relates to supports for radiators or the like, its object being to provide a device of this character which will allow the 15 radiator to be supported above the floor and allow the space below to be easy of access, so as to permit a carpet to be laid or taken up without removing or lifting the radiator, at the same time providing means for compensating 20 inequalities in the floor, and so permitting the radiator to be leveled up with facility.

My invention may be used for supporting any object which it is desired shall be permanently placed adjacent to the walls of the 25 room, but is particularly adapted for use in supporting radiators.

Said invention consists of means hereinafter fully described and particularly set forth in the claims.

30 The annexed drawings and the following description set forth in detail certain mechanism embodying the invention, such disclosed means constituting but one of various mechanical forms in which the principle of the 35 invention may be used.

In said annexed drawings, Figure 1 represents a front elevation of two supports embodying my invention supporting a radiator, and Fig. 2 represents an end elevation of such 40 radiator and a side elevation of one of said supports. Fig. 3 represents a perspective view of the upper or supporting element of such support. Fig. 4 represents a perspective view of the lower or base element of such 45 support, showing a portion thereof broken away to disclose the construction of the back portion thereof.

Each support consists of a lower base portion or element A and an upper supporting 50 portion or element B. Such base portion A

is formed with a foot a , having a flat bottom and a convex upper surface a' , such foot having sides converging from the back to the front and tapering also in vertical planes. Projecting upwardly from the rear or heel of the 55 foot is a projection a^2 , whose upper portion is formed with two laterally-located upwardly-projecting lugs $a^3 a^3$. The rear upper portion of such projection a^2 is preferably cut away to some degree to form the seat a^4 , as 60 shown in Fig. 4. The upper or supporting element B is rectangular in plan outline and of a width substantially equal to the distance between the inner upright surfaces of lugs $a^3 a^3$. The rear of element B is formed with 65 a downwardly-projecting portion b , whose front surface is preferably undercut, as shown. Intermediately of the front end of said element and said portion b and near the back end is formed a downwardly-extending lug b' and a strengthening-rib b'' , extending from lug b' toward the front of the element, as 70 shown in Fig. 2. A threaded bore is formed in lug b' , in which is seated a screw C. When these two described elements are assembled, 75 the upper one is seated upon projection a^2 , so as to cause the lug b to engage the rear undercut surface of projection a^2 , as shown in Fig. 2, the rear end of element B being seated between lugs $a^3 a^3$, such lugs preventing lateral 80 displacement of said element. Screw C is caused to bear against the front surface of projection a^2 , whereby, as will be readily seen, the position of the supporting member B may be changed and adjusted relatively to the base 85 member.

In the application of my invention as illustrated two supports are used, one at either end of the radiator. The convex surface of the foot permits a carpet to be placed over 90 same, as shown in dotted lines in Fig. 1, without exhibiting any marked irregularity in the carpet-surface. It will also be seen that by providing a free space beneath the radiator the carpet below may be easily removed or 95 replaced and kept clean.

Other modes of applying the principle of my invention may be employed instead of the one explained, change being made as regards the mechanism herein disclosed, provided the 100

means stated by any one of the following claims or the equivalent of such stated means be employed.

I therefore particularly point out and distinctly claim as my invention—

1. In a support for radiators or the like, the combination with a base portion provided with an upwardly-projecting portion cut away to form a seat, of a supporting element secured to said upwardly-projecting portion within said seat and provided with a screw for engaging said upwardly-projecting portion to render the latter and said supporting element relatively adjustable.
2. In a support for radiators or the like, the combination of a base portion having an upper convex surface, sides converging from the back toward the front, and an upwardly-projecting portion at the back, a supporting element hinged to the top of said upwardly-projecting element, and a screw seated in such

supporting element and engaging said upwardly-projecting element, whereby the former may be adjusted relatively to said base portion.

3. In a support for radiators or the like, the combination of a base having an upwardly-projecting portion at one extremity, a supporting element supported upon such portion so as to be capable of angular adjustment in vertical planes, and provided, intermediately of its ends, with a downwardly-projecting lug; and a screw seated in said lug and engaging said upwardly-projecting portion of said base.

Signed by me this 18th day of September, 1903.

GEORGE H. COLTON.
